UNITED STATES PATENT OFFICE.

GUY T. PRYOR, OF LONG BEACH, CALIFORNIA.

WELL-DRILLING BIT.

Application filed January 5, 1924. Serial No. 684,555.

To all whom it may concern:

Be it known that I, GUY T. PRYOR, a citizen of the United States, residing at Long Beach, in the county of Los Angeles, State 5 of California, have invented a new and useful Well-Drilling Bit, of which the following is a specification.

This invention relates to well drilling equipment of the character now extensively 10 employed in the drilling of oil wells.

The subterranean formations which must be penetrated in order to reach the bodies of oil vary greatly in character, and various types of tools must be employed in order to 15 accomplish the drilling speedily and in a satisfactory manner. The fish tail bit which is extensively used in rotary well drilling provides a cutting edge which lies in a plane perpendicular to the axis of the hole being 20 drilled. In other words, the intended action of the drill is that the drilling of the hole shall be accomplished by removal of material from the flat bottom of the hole. The corners on the fish tail bit are soon worn off 25 and the gauge of the bore lost, thus making reaming of the hole frequently necessary.

It is an object of my invention to provide a well drilling bit having cutting edges which are conically disposed and which bit 30 is arranged to preserve the gauge of the bore for a maximum period of time.

It is a further object of the invention to provide a drill bit which will operate satisfactorily in plastic materials, such as shale 35 and certain forms of clay which adhere to the drilling tool and interfere with the drilling action.

It is a further object of the invention to provide a well drilling bit having the inherent 40 tendency to follow a straight path. This bit is of conical form and is provided with helical cutting blades the cutting edges of which are suitably notched or interrupted to give a self-clearing effect in soft materials.

It is a further object of the invention to provide a well drilling bit of this character having the cutting blades deeply undercut 45 so that the sharpness of the blade will be maintained, and for providing ample exterior passages for the upward circulation of the lubricating mud delivered under pressure near the point of the bit.

The especial advantages of the invention 50 and further objects thereof will be made evident hereinafter.

Referring to the drawing which is for illustrative purposes only,

Fig. 1 is an elevation of a well drilling bit embodying the features of my invention. 60

Fig. 2 is a plan view taken from Fig. 1.

Fig. 3 is a fragmentary section taken on a plane represented by the line 3—3 of Fig. 2.

Fig. 4 is a section taken on a plane indicated by the line 4—4 of Fig. 1. 65

Fig. 5 is a view illustrating a use of the invention.

Fig. 6 is a view illustrating another use of the invention.

The form of my invention shown in the 70 drawing employs a tool joint pin 11 from which there downwardly extends a body 12 having a plurality of cutting blades 15 which are of conical spiral form, as shown. It is convenient to use three of the cutting 75 blades 15, as illustrated, but conditions may be found wherein it may be desirable to employ a different number of cutting blades. As shown in Figs. 2 and 4, the blades are formed of material such as steel disposed 80 between spiral surfaces 16 and 17, thus giving the blade a deep spiral undercut in such a manner that passages or grooves 19 are of sufficient size for the passage of the circulating liquid and cuttings. 85

The circulation of mud employed for lubricating and mudding up purposes is established through a central opening 20, which extends downwardly through the body 12 of the drill and communicates with laterally 90 drilled openings 21 which, as shown in Figs. 5 and 6, are disposed near the lower end of the drill so that the cuttings will be caught and carried upwardly by the circulating fluid. This circulating fluid also serves to 95 wash out the passages 19 between the blades 15. The blades 15, as shown in Fig. 1, are equipped with notches 25 which give the cutting edges 26 of the blades an interrupted effect. The notches 25 are staggered or offset with relation to each other, so that the entire surface of the conical hole being drilled by the cutting edges will be traversed by a cutting edge. 100

It will be perceived that the cutting action 105 of the bit, instead of extending across the flat bottom face of the hole being bored, is distributed over a considerably longer conical face, the gauge of the hole being established by the diameter across the upper ends 110 of the blades 15. The use of the notches 25 interrupting the cutting edges of the blades

15 reduces the rotating force required and causes the breaking up of the cuttings so that they will be readily washed away by the circulating liquid. This result serves to eliminate buoying up of the drill bit in shale formations. An important feature of the bit is that after having become worn, the gauge thereof may be re-established by heating the upper ends 30 of the blades 15 and driving 10 wedges into the narrow cuts 31 formed at the upper end of each blade, as shown in Fig. 3, thus forcing the portions 30 of the blades outwardly as indicated by the dotted lines 32.

15 When it is found impossible to remove a tool or obstruction from a well, it becomes necessary to side-track the hole, that is, to drill to one side of obstruction. My bit is especially adapted to this use as the point 20 35 thereof, Fig. 2, may be readily caused to cut to the side of an obstruction such as a drill pipe 36 lost in a previously bored hole 37.

The invention, as shown in Fig. 6, is also 25 particularly adapted to the penetrating of the cement plug 39 formed at the lower end of a casing 40 when the casing is cemented in, either for the purpose of sealing water or securing the casing preliminary to bringing 30 the well into production. An additional advantage of this drilling tool resides in the centralizing effect resulting from the conoidal form thereof. The drill in operation seats in a conoidal recess and is prevented 35 thereby from lateral movement, from which an irregularity in a well drilled by a rotary fish tail bit is often produced.

I claim as my invention:

1. A well drilling bit comprising: a central body having interrupted conoidal helical blades formed thereon and having a longitudinal central opening, said blades being widest at the top and there wider than the actuating shaft and being also spirally undercut to provide circulation passages to which a circulating liquid may be fed through laterals from said longitudinal central opening.

2. A well drilling bit comprising: a cen-

tral body having interrupted conoidal helical blades formed thereon, said blades being widest at the top and there wider than the actuating shaft and being also spirally undercut to provide circulation passages, there being a circulation passage extending downwardly through said body and opening near the lower end thereof into said circulation passages.

3. A well drilling bit comprising: a central body having interrupted conoidal helical downwardly diminishing blades formed thereon, said blades being widest at the top and there wider than the actuating shaft and being also deeply undercut and the notches therein being staggered to provide circulation passages, there being a circulation passage extending downwardly through said body and opening near the lower end thereof into said circulation passages provided by undercutting.

4. A well drilling bit comprising: a central body having conoidal helical blades formed thereon, in which notches are cut to provide an interrupted effect in the cutting edges of said blades, said blades being widest at the top and there wider than the actuating shaft and being also spirally undercut to provide circulation passages.

5. A well drilling bit comprising: a body having longitudinal blades formed thereon and means for re-establishing the gauge of said bit consisting of transverse slots extending inward from the upper ends of said blades to permit spreading of said blades radially apart from said body by the insertion of wedges.

6. A well drilling bit comprising a bit carrying interrupted and downwardly diminishing undercut spiral blades, each blade being provided with means for delivering circulating fluid immediately in advance thereof and with means for increasing, by the insertion of a wedge, the lateral extension of its uppermost and widest part.

In testimony whereof, I have hereunto set my hand at Los Angeles, California, this 29th day of December, 1923.

GUY T. PRYOR.
